UNITED STATES PATENT OFFICE.

PORTER L. BLISS, OF SAN FRANCISCO, CALIFORNIA.

COMBINED REFRIGERATOR AND ICE-CREAM FREEZER OR WATER COOLER.

Application filed January 27, 1920. Serial No. 354,456.

To all whom it may concern:

Be it known that I, PORTER L. BLISS, a citizen of the United States of America, and a resident of San Francisco, county of San Francisco, and State of California, have invented certain new and useful Improvements in Combined Refrigerators and Ice-Cream Freezers or Water Coolers, of which the following is a full and clear specification.

10 The object of this invention is to provide a simple portable refrigerator, especially adapted for home use, the construction being such that the apparatus may be arranged for use either as an ice cream freezer or as a

15 water cooler in addition to a refrigerator, as more fully hereinafter set forth.

In the drawings—

Fig. 1 is a vertical sectional view showing the apparatus as a combined refrigerator and

20 ice cream freezer;

Fig. 2 is a similar view showing the apparatus as a combined refrigerator and water cooler;

Fig. 3 is a horizontal sectional view on the

25 line 3—3 of Fig. 1;

Fig. 4 is a horizontal sectional view through the dasher-stem looking downwardly;

Fig. 5 is a fragmentary perspective view

30 of the upper portion of the dasher;

Fig. 6 is a detail perspective view of the

35 lower end of one of the agitators;

Fig. 7 is a detail perspective view of one

40 of the can-retaining keepers.

In the drawings, *a* designates a double metal-wall can having a double bottom and a double cover *b*, the space between these walls being packed with a suitable insulating medium, preferably the following special

45 medium: 40% to 65% diatomaceous earth, combined with 5% to 10% amorphous carbon (charcoal), 5% to 10% silicon dioxide (fine sand), 2% to 3% sodium chloride (common salt), 10% to 15% aluminum silicate (clay), and 5% to 10% calcium sulphate (gypsum), thereby producing a low-cost earthy mixture, light and friable, which has exceptional qualities for the prevention of heat penetration and the retaining of the

50 cold atmosphere caused by the ice and salt, which is placed in the casing.

A metal can *c* for ice cream, sherbets, etc. is anchored on a false bottom *d*, this false bottom *d* being a metal plate unprovided

55 with insulating material and having a water-and-air-tight connection with the inner face

of the wall of the casing to thereby form a separate refrigerator chamber below for the reception of various food articles. The ice is placed in the upper chamber upon said 60 false bottom *d*, so that the roof of the refrigerator chamber forms a bottom for the ice receptacle. This bottom *d* consists preferably of a thin, galvanized iron partition only and its special advantage is that it ensures a very low temperature in the refrigerator chamber below, this low temperature being maintained in this chamber by the insulated outer and bottom walls of the 65 casing. This refrigerator chamber is provided with a suitable door *e*.

The freezer can *c* is anchored to the false bottom *d* by any suitable means which will permit the can to be removed from the casing entirely, as shown in Fig. 2, thereby 70 permitting the casing to be used as a water cooler, a suitable draw-cock *f* being provided for the water chamber thus formed. The upper part of the water chamber may be used for refrigerating purposes by 75 inserting a removable wire mesh or foraminated support *g* at a point above the ice and water. When the freezer can is thus removed, it is obvious that the interior of the casing must be scalded out and drained 80 through the stop-cock before the ice and drinking water are placed therein. The diatomaceous insulation with which the ice and water are surrounded retains the low 85 temperature required for a comparatively long period of time, experience having shown that ice water may be maintained at a low temperature for a period of from 10 to 12 hours with a much smaller quantity of ice than is required with the ordinary 90 commercial cooler. It will be observed that whether the upper compartment be used as a refrigerator for an ice cream can or as a water cooler, the refrigerating effect will be transmitted directly through the non-insulating bottom *d* to the refrigerating 95 chamber below and thus maintain that chamber at a desirably low temperature.

I prefer to anchor the freezer can only 100 by means of a cleat bar *h* fastened to the bottom of the can and having its ends projecting radially beyond the sidewall of the can. A pair of keepers *i* fastened to the false bottom *d* are adapted to be engaged by the projecting ends of the cleat bar to clamp 105 the cleat bar to the false bottom. To secure the can to the false bottom, it is simply nec-

essary to rotate the can bodily until the projecting ends of the cleat bar *h* wedge under the keepers *i*; and to remove the can it is simply rotated in the opposite direction 5 until the ends of the cleat bar are free from the keepers.

I prefer also to use a special form of dasher arranged in the can. This consists of the main dasher consisting of a central 10 bar *j* provided with lateral arms *k* and having attached to their outer ends vertical scraper-blades *l* which, when the dasher is rotated, scrape the can. By rotating the central bar *j* by means of an upstanding 15 shaft *m*, to whose upper end is removably secured a hand-wheel *n*, it will be observed that the contents of the can may be given a rotary motion. To vertically agitate the contents of the can, I provide a vertically- 20 sliding appliance consisting of a pair of tubes *o* connected together by a tubular shaft *p* having a hand-wheel *q* attached to its upper end, just under the hand-wheel *n*. The tubular members *o* are adapted to slide 25 vertically on opposite sides of the central bar or staff *j*, a T-shaped rib *r* being provided on each side of said central bar or staff *j* to serve as guide-ways for said tubular members *o*. By removing the hand- 30 wheel *n*, the vertical tube members *o* may be vertically reciprocated on the guide-ways *r*, the main dasher being prevented from moving up and down with these tubular members *o* by having the upper ends of the 35 scraper-bars *l* extend high enough to engage under the cover *s* of the cream can. To agitate the contents of the can when the tubular members *o* are thus worked up and down, I provide each of these tubular mem- 40 bers at its lower end with a fan-shaped arrangement of paddles *t*. With this arrangement, it will be observed that the contents of the can may be agitated without cranks or gears. The freezing properties due to 45 the diatomaceous insulation in the walls of

the main can, causes rapid solidification of the liquid contents of the cream can, and, in order to avoid complete solidification of the contents, it is only necessary, every two or three minutes after the can is placed in position, to give the dasher three or four half turns by means of the hand-wheel *n*. This produces the desired circular agitation and prevents the contents from freezing too quickly to the sides of the can; and, in order 55 to produce a more homogeneous ice cream, the vertical dashers or paddles may be operated. Two or three operations of these vertical agitators every few minutes, following the circular agitation above described, agitates the contents sufficiently to provide a superior quality of ice cream or sherbet, the time required being from fifteen to twenty minutes.

The nature and scope of the invention 60 having been thus indicated and its preferred embodiment having been specifically described, what is claimed as new is:

1. In an ice-cream freezer, a cream-can having a cover, a main rotary dasher held 70 down in the can by means of said cover and having an operative shaft extending up through said cover, a pair of supplemental dashers or agitators mounted to reciprocate on said main dasher and having an opera- 75 tive means extending up through said cover, for the purpose set forth.

2. In an ice-cream freezer, a cream-can, a main rotary dasher having on opposite sides vertical flanged ribs, a pair of supplemental 80 dashers or agitators mounted to slide on said ribs and having means for reciprocating them extending up through the cover of the cream-can.

In testimony whereof I hereunto affix my 85 signature.

PORTER L. BLISS.
